(57) **CLAIM**

The ornamental design for a piezoelectric buzzer, as shown and described.

DESCRIPTION

FIG. 1 is a perspective view of the piezoelectric buzzer showing the design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side view thereof; and,

FIG. 7 is a right side view thereof.

The broken line showing is included for the purpose of illustrating portions of the "article" and forms no part of the claimed design.
